UNITED STATES PATENT OFFICE.

ELMER J. NICHOLS, OF PAWTUCKET, RHODE ISLAND, ASSIGNOR TO THE
J. M. CARPENTER TAP AND DIE COMPANY, OF SAME PLACE.

TAP AND REAMER WRENCH.

SPECIFICATION forming part of Letters Patent No. 532,285, dated January 8, 1895.

Application filed June 20, 1894. Serial No. 515,096. (No model.)

To all whom it may concern:

Be it known that I, ELMER J. NICHOLS, of Pawtucket, in the county of Providence and State of Rhode Island, have invented a new and Improved Tap and Reamer Wrench, of which the following is a full, clear, and exact description.

The object of the invention is to provide a new and improved tap and reamer wrench, which is comparatively simple and durable in construction, and arranged to strengthen the handles, and to permit of conveniently opening and closing the jaws without the operator turning the handles.

5 The invention consists in certain parts and details, and combinations of the same, as will be hereinafter fully described and then pointed out in the claims.

Reference is to be had to the accompanying drawings, forming a part of this specification, in which similar letters of reference indicate corresponding parts in all the views.

Figure 1 is a plan view of the improvement. Fig. 2 is a sectional side elevation of the same, 25 on the line 2-2 of Fig. 1. Fig. 3 is a sectional side elevation of the sleeve. Fig. 4 is a sectional plan view of a modified form of the improvement; and Fig. 5 is a similar view of another modified form of the improvement.

30 The improved tap and reamer wrench is provided with the stock A, formed with the usual elongated opening A', in which is held the fixed jaw B and the movable jaw C. The ends of the stock A are formed with the necks

35 A² and A³, of which the former terminates in a handle D, forming an integral part of the neck A². The other neck A³ is connected by a sleeve E with a second handle F, provided with a reduced portion forming a rod F', ex-

40 tending through the neck A³, and connected in any suitable manner with the movable jaw C. The sleeve E as illustrated in Figs. 1, 2 and 3 is formed with two internal screw threads E' and E², of which one is right-hand

45 and the other left-hand, as plainly illustrated in Fig. 3. The thread E' screws on the threaded portion A⁴ of the neck A³, while the other thread E² screws on the threaded part F² of the handle F.

50 Now, it will be seen that when the operator

turns the sleeve E in one direction the handle F will be moved bodily inward so as to impart by its rod F', an inward sliding motion to the movable jaw C, to move the latter in contact with the tap or reamer to be engaged by the wrench. When the sleeve E is turned in the opposite direction the handle F will be moved bodily outward so as to impart an outward sliding motion to the movable jaw C, to disengage the jaws B and C from the tap or reamer.

It will be seen that by the construction described, the sleeve E connects the neck A³ with the handle F without weakening any of the parts; on the contrary making a strong 65 connection between the neck and the handle, to prevent breaking of the parts in case the wrench undergoes a heavy strain. It will further be seen that the handle F does not turn, but is moved bodily longitudinally inward or 70 outward, according to the direction in which the sleeve E is turned, so that the operator in manipulating the device can retain a firm hold of the handle F, while turning the sleeve E to open or close the movable jaw C.

75 As illustrated in Fig. 4, the sleeve E³ is provided with a single internal thread E⁴, engaging a thread A⁵ formed exteriorly on the neck A⁶ of the stock A⁷, the outer end of the said sleeve E³ being mounted to turn on the handle F⁸ connected by the rod F⁴ with the movable jaw in the same manner as above described in reference to Fig. 4.

In order to mount the sleeve E³ so as to turn on the handle F⁸, I provide a collar or nut G, 85 screwed on the reduced portion of the handle F⁸ inside of the outer end of the sleeve E³. Now, by turning this sleeve E³ in one direction it rotates on the handle F⁸, but screws on the thread A⁵, to move the sleeve and handle inward and consequently the movable jaw C toward the fixed jaw B. By turning the sleeve in the opposite direction, the handle F⁸ is moved bodily outward to open the jaw C.

90 As illustrated in Fig. 5, the sleeve E⁵ is 95 mounted to turn on the neck A⁸ of the stock A⁹, and is provided with an internal screw thread E⁶ engaging a screw thread F⁷ arranged externally on the handle F⁶ connected by the rod F⁸ with the movable jaw, as previously 100

described in reference to Fig. 1. A collar or nut G' screws on the outer end of the neck A⁸, to hold the sleeve E⁵ in place and to permit the same to turn loosely on the neck A⁸, 5 without moving longitudinally thereon. Now, it will be seen that by turning the sleeve E⁵ in one direction, the handle F⁶, rod F⁸ and movable jaw C are moved inward to close the jaws, and by turning the sleeve E⁵ in the opposite direction the said parts move outward to open the jaws.

It is expressly understood that by the several constructions described, the handle connected with the movable jaw C does not turn, 15 but is moved bodily inward or outward so as to open or close the jaws B and C.

Having thus described my invention, I claim as new and desire to secure by Letters Patent—

20 1. A tap and reamer wrench, comprising a stock having a threaded neck, a sleeve having a double screw thread of which one screws on the said neck, a handle having a threaded end screwing in the other thread of the said 25 sleeve, and a movable jaw held in the said

stock and connected with the said handle, substantially as shown and described.

2. A tap and reamer wrench, comprising a stock having a threaded neck, a sleeve screwing on the said neck, and a handle on which the said sleeve is mounted to turn, the said handle being connected with the movable jaw fitted to slide in the stock, substantially as shown and described. 30

3. A tap and reamer wrench, comprising a stock having a neck, a handle in axial alignment with said neck, and having an extension passing through the neck of the stock, the extension having a movable jaw mating a jaw in the stock, and a joint adjustably uniting 35 said neck and handle, and consisting of an external sleeve fitting over and adapted to rotate on both the neck and handle, and engaging both for moving them toward and from each other, substantially as described. 40
